UNITED STATES PATENT OFFICE

ALFRED PARTLOW, OF LINCOLN PARK, MICHIGAN, ASSIGNOR, BY MESNE ASSIGNMENTS, TO UNITED STATES HOFFMAN MACHINERY CORPORATION, OF NEW YORK, N. Y., A CORPORATION OF DELAWARE

LOCKING MECHANISM FOR EXTRACTOR COVERS

Application filed March 26, 1928. Serial No. 264,763.

This invention relates to locking devices and particularly to devices for locking the cover of an extractor in its closed position.

An object of the invention is to provide a device that will automatically lock the cover of a centrifugal extractor against being opened as long as the basket of the extractor is being driven.

Another object is to provide a device of the described character that will have one or more of its locking parts adapted to yield if power is applied to the basket while the cover is in open position, whereby breakage or damage of parts is avoided.

Still another object is to provide a locking mechanism for the cover of an extractor, comprising a part rotatively driven in common with the basket of said extractor and adapted when so driven to assume a position restraining the cover from being opened.

These and various other objects the invention attains by the construction hereinafter described and illustrated in the accompanying drawings, wherein:

Figure 1 is a view in side elevation and partial section of an extractor and the basket-drive mechanism thereof, showing the extractor cover equipped with the herein-described locking mechanism.

Figure 2 is a fragmentary plan view of a portion of said extractor, showing in detail said locking mechanism.

Figure 3 is a vertical sectional view of the same taken upon the line 3—3 of Figure 2.

Figure 4 is a similar section showing, however, the opened position of the cover and the corresponding positions of the parts of the locking mechanism.

Figure 5 is a cross-sectional view through the casing of the locking device taken upon the line 5—5 of Figure 3.

Figure 6 is a perspective detail view of a plunger cam employed in the herein disclosed mechanism.

Figure 7 is a cross sectional view of the casting taken on line 7—7 of Figure 3.

In these views reference character 1 designates the curb of an extractor and 2 the usual rotative, perforated basket disposed within said curb. While so far as concerns the

present invention, said basket may be driven in any desired manner, there is illustrated (see Figure 1) a drive mechanism comprising a shaft 3 extending centrally and vertically into the curb through an opening 4 in the bottom thereof, and suitably driven as, for example, by a chain 5 extending from a suitable sprocket member 6 on the lower end of said shaft to an electric motor 7 or the like.

The curb is provided with a suitable cover 8, adapted to seat upon the rim of said curb and hingedly connected to said rim through a pintle 9 jointly carried by a pair of hinge leaves 10 and 11, secured by rivets 11a or the like, respectively to the cover 8 and to said rim.

The locking mechanism for the cover 8 comprises a radially slidable bolt 12 connected at its inner end to the hinge leaf 10 by a swinging link 13 and adapted to slide to and from the tub axis in a socket 14 diametrically formed in the top portion of a cylindrical tubular casing 15. The latter is mounted upon the curb, preferably vertically, by any suitable means, such as a bracket member 16 integrally projecting from said casing and rigidly secured by bolts 17 or the like, to the curb rim. Said casing is preferably capped at its upper end, as indicated at 18 and has a bushing 19 secured in its lower end by set-screws 20 or the like. Rotatively seating on said bushing and occupying the lower portion of the casing is a tubular cam 21 formed at its upper end with a pair of oppositely spaced teeth 22 of inverted V shape. The mid-portion of the casing is occupied by a tubular plunger 23, formed at its lower end with a pair of opposed V-shaped cam teeth 24, duplicating those of the cam 21, and said plunger is formed, longitudinally thereof, with a slot 25 in which is engaged a pin 26 radially secured in the casing. Said slot affords the plunger a sufficient lengthwise play to permit the teeth of the plunger cam and rotary cam to inter-mesh as shown in Figure 4 when the rotary cam is stationary or to permit the rotation of the cam to raise the plunger to the position shown in Figure 3. The width of the slot 25 exceeds the diameter of the pin 26.

Figure 5 is a cross-sectional view through the casing of the locking device taken upon the line 5—5 of Figure 3. The width of the slot 25 exceeds the diameter of the pin 26.

26 to allow the plunger a limited rotation for reasons hereinafter set forth.

In the upper portion of the casing 15, a relatively short plunger 27 is slidable, and is spaced above and supported by the plunger 23 through a coiled spring 28, the arrangement being such that the two plungers 23 and 27 are adapted normally to shift as a unit as regards vertical travel. Thus, when said plunger is raised, the plunger 27 obstructs the socket 14 as is shown in Figure 3, while in the lowered positions of said plungers, the plunger 27 is disposed below said socket, as Figure 4 illustrates. It is to be understood that the spring 28 is not subjected to appreciable compression through normal travel of the two plungers.

For driving the cam 21, a coupling pin 29, journaled in the bushing 19 projects into said cam and rigidly carries a driving pin 30 which projects into a diagonal slot 31 formed in said cam. Below the casing 15, a drive connection to the pin 29 is established from one end of a flexible shaft 32 which at its other end is adapted in any suitable manner to be driven by the motor 7. (See Figure 1.)

In the use of the described construction, when the basket 2 is stationary the plungers 23 and 27, of their own weight, drop to the lowered position shown in Figure 4, in which the teeth 24 engage between the teeth 22 of the cam 21. Under these conditions the cover 8 is free to be raised, since the plunger 5 is free to slide from its position disclosed in Figure 3 to that shown in Figure 4 during such raising. When the basket comes to rest, after an extracting operation, the teeth 24 of plunger 23 will not necessarily be in a position to drop directly between the teeth 22, but the weight of said plunger and the parts which it carries is adequate to effect such slight relative rotation of said plunger and of the cam 21 as will allow a full descent of both plungers.

When the cover 8 is lowered, prior to energizing the motor 7, power is applied both to the basket 2 and to the shaft 32 whereby the cam 21 is continuously rotated, resulting in a cam action of the teeth 22 upon the teeth 24 to raise and maintain the plunger 23 in the position shown in Figure 3. In this position said plunger so obstructs the socket 14 as to prevent outward sliding of the bolt 12 and consequently locks the cover 8 in its lowered or closed position. Thus raising of the cover 8 during rotation of the basket 2 is very positively prohibited.

If through negligence the motor 7 is energized while the cover 8 occupies the raised position shown in Figure 4, any resulting damage or breakage of parts is avoided through the presence of the spring 28, which allows the plunger 23 to be elevated through rotation of the cam 21, although the bolt 12 prevents upward actuation of the plunger 27.

Thus the device secures the desired result of an automatic locking of the cover in closed position when the basket is being driven, while avoiding breakage in the event that a drive is applied without first closing said cover.

It is of course to be understood that the particular means disclosed for driving the rotary cam 21 in common with the basket is merely by way of example, it being obviously feasible to establish the desired common drive in a great variety of other ways.

While it will be apparent that the illustrated embodiment of my invention herein disclosed is well calculated to adequately fulfill the objects and advantages primarily stated, it is to be understood that the invention is susceptible to variation, modification and change within the spirit and scope of the subjoined claims.

What I claim is:

1. The combination with an extractor comprising a curb, a cover for said curb, and a basket rotative in said curb, of a locking device for said cover comprising a casing secured to said curb, a bolt slidable in said casing, a connection between said bolt and cover for holding the cover closed in one position of said bolt, a plunger slidable in said casing into and out of the path of said bolt and adapted to maintain the locking position of the bolt when disposed in the path of the bolt, a cam member journaled in said casing for actuating said plunger into the path of the bolt, and a common drive means for said cam member and the basket.

2. The combination with an extractor comprising a curb, a cover for said curb, and a basket rotative in said curb, of a locking device for said cover comprising a sliding plunger having a cam portion, means restraining said plunger from rotation, means for restraining said cover against opening movement in one limiting sliding position of said plunger, a cam member rotatively co-acting with the cam portion of said plunger to shift the plunger to its locking position, and a common drive means for said cam member and basket.

3. The combination with an extractor comprising a curb, a cover for said curb, and a basket rotative in said curb, of a casing exteriorly secured to said curb, a plunger slidable in said casing, having a substantially V-shaped cam portion, means carried by said casing for restraining said plunger from rotation, means co-acting with said plunger for locking the cover against opening movement in one limiting sliding position of said plunger, a rotative cam member journaled in said casing, and formed with a substantially V-shaped cam tooth co-acting with said plunger cam to actuate the plunger to locking position responsive to rotation of said cam member, and a common means for

driving said rotative cam member and the extractor basket.

4. The combination with an extractor comprising a curb, a cover for said curb, a basket rotatable in said curb, a prime mover and a drive connection to the basket from said prime mover, of mechanism for locking the cover in closed position, a rotary control element for said mechanism, adapted, when driven, to maintain the cover closed, and a flexible shaft establishing a drive from said prime mover to said control element.

5. The combination with an extractor comprising a curb, a basket rotative therein, and a cover for said curb, of a lock mechanism for said cover comprising a pair of coacting coaxial cam members, one rotatively effective to slide the other to a locking position, and a common means for driving the basket and said rotative cam member.

6. The combination with an extractor comprising a curb, a cover for said curb hinged for opening and closing travel, and a basket rotative in said curb, of a sliding bolt, a connection between the cover and bolt, effecting sliding of the bolt responsive to opening or closing travel of the cover, a plunger slidable into and out of the path of said bolt and restraining the cover from opening travel when engaged in the path of the bolt, a cam member rotatable coaxially with said plunger, to actuate the plunger into the path of the bolt, and a common drive means for said cam member and basket.

35 7. The combination with an extractor comprising a curb, a cover for said curb, and a basket rotative in said curb, of a sliding plunger having a substantially V-shaped portion, means for guiding said plunger and for restraining it from rotation, means coacting with said plunger for locking said cover against opening movement in a limiting position of the plunger, a cam member journaled coaxially with said plunger and formed with a substantially V-shaped cam tooth coacting with the cam portion of said plunger to actuate the plunger to cover-locking position, responsive to rotation of said cam member, and a common means for driving said rotative cam member and the extractor basket.

In witness whereof I hereunto set my hand.
ALFRED PARTLOW.
